UNITED STATES PATENT OFFICE.

JOHN WALTER WOLFF, OF RURALHALL, NORTH CAROLINA.

LACE-CARD.

SPECIFICATION forming part of Letters Patent No. 782,092, dated February 7, 1905.

Application filed June 6, 1904. Serial No. 211,322.

To all whom it may concern:

Be it known that I, JOHN WALTER WOLFF, a citizen of the United States, residing at Ruralhall, in the county of Forsyth and State of North Carolina, have made certain new and useful Improvements in Lace-Cards, of which the following is a specification.

My invention is an improvement in cards especially designed for application to lace already wound, although it may be employed in winding lace on the card; and the invention consists in certain novel constructions and combinations of parts, as will be herein-after described and claimed.

In the drawings, Figure 1 is a face view of a card with the sections in contracted position. Fig. 2 is a similar view with the sections expanded and secured by the clip. Fig. 3 is a detail perspective view showing the two sections of the card detached. Fig. 4 is a detail perspective view of the clip for holding the card-sections in expanded position. Fig. 5 is a detail perspective view of a clip which may be employed for securing the end of the lace or other material held on the card, and Fig. 6 shows a somewhat different construction from that shown in Figs. 1 and 2.

As before suggested, my invention is especially designed to be used with lace already wound and without containing a card, the improved device being adapted to be contracted at one end, as shown in Fig. 1, so it can be readily inserted in the bolt of lace and then spread to the position shown in Fig. 2, where-35 in it will securely hold the bolt in place, and to be secured in such position by a clip, such as best shown in Fig. 2.

As shown in Figs. 1, 2, and 3, the card consists of the sections A, which may be alike and may be made of cardboard or other suitable material and are preferably of the same size and shape, being made wider at one edge than at the other. The two sections A are lapped upon each other and are jointed together at their wide edges, as shown in Figs. 1 and 2. As shown in Figs. 1 and 2, the joint or pivot at B may be effected by means of an eyelet, rivet, or clip, as this operates to securely connect the sections together and at 50 the same time permits the movement of same

in adjusting to the different positions in expanding and contracting the card.

In operation the card may be contracted to the position shown in Fig. 1 and inserted in the bolt of lace or other material which it may be desired to hold on the card and the card be then expanded to the position shown in Fig. 2 to bind within the bolt of lace and be held in such position by the clip C, such clip operating to hold the card securely in its expanded position to retain the bolt of lace thereon as desired.

As shown in Figs. 1 and 2, I may employ a clip D for holding the end of the lace on the card, such clip being shown in detail in Fig. 5.

It will be noticed that the clips C and D are bent at their free ends to form loops C' and D' for holding the lace without any injury to the latter. I may, however, employ the ordinary clip, such as shown in Fig. 6, and in the latter construction I join the card-sections together at one edge by a clip E and provide a clip E' for holding the card-sections when expanded from the dotted-line position shown in Fig. 6 to the full-line position shown in the same figure. It will be understood that this construction shown in Fig. 6 may be employed when desired without departing from some of the broad principles of my invention.

Manifestly my improved card may be employed for holding ribbon, tape, and the like, and the clips may be employed for fastening the ends of ribbon, tape, &c., as may be desired.

Having thus described my invention, what I claim as new, and desire to secure by Letters Patent, is—

1. The improved lace-card herein described, comprising the two sections lapped upon each other and pivoted together near one edge whereby they may be adjusted at their other edges to contract the card for insertion in a bolt and then expanded to secure the bolt, and a clip securing the two sections together at the edge opposite the pivot, whereby to hold the same in a bolt, substantially as and for the purposes set forth.

2. A lace-card composed of sections lapped upon each other and pivoted near one

edge and adapted to be enlarged by movement on said pivot after being inserted in a bolt of lace in order to hold the latter, substantially as set forth.

5. 3. A lace-card consisting of two sections, means for joining said sections together near one edge the sections being adjustable pivotally on said joint, whereby the card may be contracted at the other edge for insertion in 10 a bolt and then expanded within the bolt and means for holding the card in expanded position, substantially as set forth.

4. A lace-card consisting of two sections made narrower toward one edge, means joining the sections together at their wide edges, 15

and a fastening for holding the sections together at their narrower edges, substantially as set forth.

5. A lace-card composed of two sections narrowing toward one edge, an eyelet pivoting said sections together at their wide edges, and a clip for holding the sections together at their narrower edges whereby to secure the same when expanded within a bolt of lace or the like, substantially as set forth. 20

JOHN WALTER WOLFF.
